UNITED STATES PATENT OFFICE.

JOHN F. DORSEY, OF WASHINGTON, DISTRICT OF COLUMBIA, ASSIGNOR OF
ONE-HALF TO ROBERT G. CALLUM, OF SAME PLACE.

ELECTRIC BURGLAR-ALARM SYSTEM.

SPECIFICATION forming part of Letters Patent No. 651,325, dated June 5, 1900.

Application filed October 7, 1899. Serial No. 732,904. (No model.)

To all whom it may concern:

Be it known that I, JOHN F. DORSEY, a citizen of the United States, residing at Washington, in the District of Columbia, have invented new and useful Improvements in Electric Burglar-Alarm Systems and Apparatus Used Therein, of which the following is a specification.

My invention relates to the class of electric burglar-alarm systems in which a signal or alarm is given at a central office or other distant place whenever an attempt is made to enter the guarded structure. In prior systems of this character each building is equipped with devices, which operate to cut out a resistance whenever a door or window is opened, so that the current of the connecting line will be so varied as to cause a circuit-closer in the form of a galvanometer to close an alarm-circuit at the central office and give an alarm. It will be readily seen that with systems of this character the same alarm will be given by the grounding of the current at any point along the connecting line, and it is therefore not known when an alarm is given whether it is caused by an attempt to enter the guarded structure or by an accidental grounding of the line-current.

The resistance and the devices which are attached to the doors and windows of the protected structure for cutting said resistance out of the main line are usually arranged within a local circuit adapted to be cut into and out of the main line, so that when used for the protection of business establishments the system may be readily connected at night and disconnected during business hours, when protection is not required. The main line is always kept in closed circuit by ground connections at each end, and the cutting in or out of this local circuit, which I will term the "protecting-circuit," will cause a variation of the galvanometer or circuit-closer at the central station, and in order that the cause of such variation may be known certain signals are first given by parties in the protected building by means of a key or other device. With one familiar with the working of the system it is an easy matter to ground the wire outside of some business establish-

ment just before the closing hour and by the use of a battery and key receive and answer the signals and after the protecting-circuit has been cut into the main line measure its resistance. The proper signal can then be given to the central office and the ground connection removed without detection. The next night the line can again be grounded, the signals received and transmitted, and a resistance equal to that of the protecting-circuit cut into the line, so that the protected building will be removed from the system without detection.

The main object of my invention is to provide means for indicating by a suitable signal or alarm at the central office a short circuit or grounding of the line-wire outside of the protected building whenever it occurs, regardless of whether the protecting-circuit is in or out of circuit therewith.

With the systems now in use the alarm-circuit is closed by the galvanometer or circuit-closer when the protecting-circuit, with its resistance, is cut out of the main line, so that any accidental grounding of the latter will not be discovered until it is attempted to place the system in operative condition by cutting in the protecting-circuit. It is then found that the galvanometer will fail to respond and that the system is inoperative. The accidental grounding of the main line is not of infrequent occurrence, and it almost invariably happens that although it may occur early in the day the fact remains undiscovered until some business establishment is closing for the night, when it is too late to locate and remedy the difficulty. At such times watchmen are sent to guard the building until daylight, when the trouble may be more readily located and removed. These defects are remedied by the main feature of my invention, which consists in the employment of circuit-closing contacts controlled by variations in the main-line current for closing separate or branch alarm-circuits, so adjusted with reference to each other and to a resistance in the main line that the circuit controlled by one set of contacts will remain open after the circuit controlled by the other set has been closed by a short circuit in the

protecting-circuit and until said resistance has been cut out by a short circuit in the main line, as hereinafter explained in detail.

Another feature of my invention relates to 5 the independent arrangement of the protecting-circuit with reference to the resistance controlled thereby and the division of the protecting-circuit into sections, whereby a short circuit occurring therein may be accurately and quickly located and the other sections 10 remain unaffected thereby.

After a detail description of my invention the features deemed novel will be specified in the claims hereunto annexed.

15 Referring to the drawings, Figure 1 is a diagrammatic illustration of a system embodying my invention in which two separate circuit-closing instruments are employed in connection with the alarm-circuits. Fig. 2 is a 20 diagrammatic illustration of an alarm-circuit in which a single circuit-closing instrument is employed. Fig. 3, in front view, illustrates another form of circuit-closing instrument and its connections with an alarm-circuit. 25 Fig. 4 is a central vertical section of the instrument illustrated in Fig. 3, taken on line $x-x$ of said figure; and Fig. 5 is a view of the movable contacts or needles and their armature detached from said instrument.

30 Referring to Fig. 1, that portion of the system which is located at the central office is inclosed within the dotted line y and that portion located within the protected structure is inclosed within the dotted line z . It is to 35 be understood that each building under protection of the system is equipped with numerous devices which operate to break or short-circuit an electric current whenever a door or window is opened or an attempt is 40 otherwise made to effect an entrance. In prior systems of this character these devices have been arranged in a single circuit, which is cut into the main circuit, so that each device within the protecting-circuit is directly connected to the central office. In my improved 45 system the protecting-circuit has no direct connection with the main-line current, and it is divided into sections representing floors or other divisions of the building, and each section is connected with an annunciator, so that when any of the devices therein are operated to break or short-circuit the current the annunciator will indicate the particular section in which such device is located. The 50 annunciator is arranged to cut out a resistance in the main line for giving the signal to the central office, as will be explained.

The protecting-circuit A (illustrated in diagram in Fig. 1) may be divided into any number 55 of sections; but, as shown, it is divided into two sections a and a' . Section a is composed of two wires 1 and 2, connected to opposite poles of a local battery a^2 and extending therefrom in a parallel course to all windows, doors, and other exposed places of that portion of the building to be covered thereby.

These wires 1 and 2 are connected to an electromagnet b of an annunciator B and form a closed circuit through the battery a^2 . Between the wires 1 and 2 are arranged any of 70 the well-known devices a^3 , which short-circuit or break the current whenever a door or window is opened, as will be readily understood. The devices a^3 are shown as short-circuiting devices; but it is to be understood 75 that circuit-breaking devices may be substituted to perform the same service. Section a' is similar in all respects to section a , its two wires 3 and 4 being connected to the same battery a^2 and to an electromagnet b' of an- 80 nunciator B, and it is provided in the same manner with short-circuiting devices a^3 , the only difference between the two sections a and a' being that they cover different floors or sections of the protected building. The 85 electromagnets b and b' hold pivoted armatures b^2 b^3 in engagement with annunciator-drops b^4 b^5 and away from contacts b^6 b^7 , connected to the main-line wire D. The armatures b^2 b^3 are provided with springs b^8 b^9 , 90 tending to draw them away from their magnets and into engagement with the contacts b^6 b^7 , and they are connected to ground C by wires 5 and 6, respectively.

The main-line wire D, which connects the 95 central office, is connected to arm e of a two-pointed switch E, one point of which is connected by wire 7 to ground C and the other point connected to a resistance F and then to ground C by wire 8. Connected to line-wire 100 D is a branch wire 9, to which the contacts b^6 and b^7 are connected by wires 10 and 11, respectively. The line D is connected at the central office to one pole of a battery d , the other pole of which is connected to ground C 105 by wire 12.

When the guarded structure or building is under protection of the system, the arm e of switch E is turned in the position shown, so that the main current will pass from said 110 switch through resistance F to ground. It will now be understood that should any of the devices a^3 in the protecting-circuit be operated to short-circuit the section in which it is located the resistance F will be cut out of 115 the main circuit in the following manner: Should, for instance, any of the devices a^3 of section a be operated, the magnet b of the annunciator will be cut out of the local circuit and its armature b^2 will be drawn by its spring 120 b^8 into engagement with contact b^6 and the drop b^4 will at the same time be permitted to fall to indicate that the trouble is in that section of the building covered by section a . The main current will then pass from line-wire 125 D through wires 9 and 10 to armature b^2 , and then to ground C through wire 5. The resistance F will thus be cut out of the main-line circuit and cause a galvanometer at the central office to indicate the fact by closing an 130 alarm-circuit, as will be presently explained. The resistance F will in like manner be cut

out of the circuit by the operation of any of the devices a^3 of section a' . During the time protection is not desired the arm of the switch E is turned for shifting the main-line current 5 directly to ground through wire 7, the main line being thus always kept in closed circuit, so that any break in the line-wire may be promptly discovered, and also to admit of signals to and from the central office by means 10 of a suitable key. (Not shown.)

Within the main line D at the central office is the usual circuit-closer G, controlled by the main-line current for closing a local alarm-circuit whenever resistance F is cut out by a 15 break or a short circuit. This circuit-closer is in the form of a galvanometer, the needle g of which forms one terminal of the alarm-circuit, the other terminal of said circuit being connected to two fixed contacts g' and g^2 , with 20 which the needle engages when moved in either direction by variations in the main-line current.

The arrangement of the alarm-circuit may be widely varied, and any suitable instrument or instruments may be employed for giving the alarm. In Fig. 1 I show both a bell H and an annunciator I, the latter consisting of a drop i , retaining-armature i' , and electromagnet i^2 . These are connected in 25 circuit with the circuit-closer G as follows: From battery J a wire 13 connects with bell H, which is connected by wire 14 to fixed contact g' , which in turn is connected by wire 15 to fixed contact g^2 . Wires 14 and 15 are 30 provided with switches h and h' respectively, which are used to open the circuit for preventing a continuous ringing of the alarm when the circuit is closed by the circuit-closer G. The galvanometer-needle or movable contact 35 40 g is connected by wires 16 and 17 with the electromagnet i^2 of the annunciator, and the latter is connected by wire 18 with battery J. The alarm-circuit, as thus far described, is in all essential respects the same as that now 45 50 55 60 65 70 75 80 85 90 95 100 105 110 115 120 125 130 135 in use. The needle of the galvanometer G is adjusted to stand midway between the contacts g' g^2 when the resistance F is in the main line, so that when said resistance is cut out by a short circuit in the protecting-circuit it will be deflected against contact g^2 and close the alarm-circuit, and thus cause the bell H and annunciator I to be operated, as will be understood. If, then, the switch h' be opened for breaking the circuit, the latter will still be in readiness to give a second signal should a break occur at any point in the main line. Should this occur, the galvanometer-needle g will move to its upright position against contact g' and again close the circuit. The switch h may then be used to again open the circuit. When the resistance F is cut out by the switch E, needle g will move against and remain in contact with contact g^2 , but before the switch is operated signals are exchanged with the central office, so that the alarm resulting from the cutting out

of the resistance F may be understood. These signals are given by the usual key and sounder, (not shown,) or they may be given by successive movements of the switch-arm e. 70

It will be readily understood that with the system as thus far described should a short circuit occur in the line-wire during the time the resistance F is out of the circuit no alarm or signal will be given, and the fact will remain undiscovered until resistance F is again cut into the circuit. It will also be understood that should a short circuit occur in the main line during the time resistance F is in the circuit the same signal will be given as 80 when one of the devices a^3 short-circuits the protecting-circuit. It will therefore not be known whether such signal is caused by a short circuit in the main line or by an attempt to enter the protected structure. These defects I overcome by providing at the central station a second circuit-closer similar to that already described. This second circuit-closer is a galvanometer K, arranged within the main-line wire D. The needle k is connected 90 by a branch wire 19 to wire 17 of the alarm-circuit already described, and in line with the needle is a fixed contact k' , connected by wire 20 to a bell H', which is in turn connected to battery J by wire 21. A second circuit is 95 thus formed, which includes the battery and annunciator of the other circuit. In order to fulfil intended requirements, the needle k of galvanometer K would ordinarily have a much greater range of movement than that 100 of the galvanometer before described, and in order to reduce this movement the needle-armature k^2 is weighted, as at k^3 , to the rear of its line of deflection, so that a greater current will be required for moving it a given 105 distance than would be the case were the needle and armature evenly balanced.

Within the main line D and just inside of the protected structure is a small resistance K', (shown in the form of a lamp,) which may, 110 if desired, be hid from view by a box or cover, (indicated in dotted lines.) As this resistance is at all times within the main-line circuit, the galvanometer G is of course adjusted so that this resistance will in no manner interfere with its operation when resistance F is cut out either by the switch E or by the operation of any of the devices a^3 , as described. The fixed contact k' of galvanometer K is so adjusted with reference to the deflection of needle k that the alarm-circuit controlled thereby will be kept open by the resistance K' after the resistance F is out of the circuit and until resistance K' is cut out by a short circuit in the main line. It will thus 115 be seen that the alarm controlled by galvanometer K will only be sounded by a short circuit which cuts out resistance K', so that should an alarm be given by the operation of galvanometer G alone it will be positively 120 known that the trouble is within the protected structure, and an inspection of the an-

nunciator B will indicate the exact locality. When the galvanometer K is operated to close the circuit controlled thereby, it is positively known that the trouble is caused by a short circuit in the main line outside of the protected structure. The closing of the circuit controlled by galvanometer K causes the sounding of bell H' and the operation of annunciator I, as will be readily understood, to prevent a continuous ringing of the bell wire 20 is provided with a switch h² for opening the circuit.

The two galvanometers G and K may be connected to operate the same alarm; but I prefer to have separate bells readily distinguishable as to sound to indicate the different character of the signals. Whenever two galvanometers are employed in the same circuit, each must operate through the resistance of the other, and while this may not be objectionable I have embodied the features of the two galvanometers in a single instrument, one form of which is illustrated in Fig. 2 in connection with a single-alarm circuit. The circuit-closing instrument L here shown is in the form of a galvanometer located as before within the main-line wire D. The needle l is connected by wire 22 with bell H², which in turn is connected by wire 23 to one pole of a battery J', the other pole of the battery being connected by wire 24 to fixed contact l' at one side of the needle l. At the other side of the needle is a spring-contact l², connected by wire 25 to battery J', and at the rear of spring-contact l² is a fixed contact l³, connected by wire 26 to fixed contact l'. The line-wire D extends to a guarded structure or building, wired and connected as before described in connection with Fig. 1. When the resistance F is in the main line, needle l is held midway between contacts l' and l² and operates to close the circuit in the same manner as the galvanometer G of Fig. 1. When the resistance F is cut out by the operation of any of the devices in the protecting-circuit or by the switch E, the needle l will be deflected against spring-contact l² and close the alarm-circuit, and should a break occur in the controlling-circuit the needle will be moved to contact l', in either case causing an alarm to be given. Switches h and h' are provided in wires 24 and 25, respectively, to open the circuit after it has been closed by either of the causes mentioned. When resistance F is out of the main line, the needle l will rest against contact l², which is made quite delicate, so that it may be easily moved by the needle should the current of the main line be in any manner sufficiently increased. In this condition the alarm-circuit is opened by the switch h' to prevent a continuous ringing of the alarm. Fixed contact l³ is adjusted to be slightly removed from spring-contact l² when resistance F is out of the main-line circuit. Should a short circuit occur to cut out resistance K', spring-contact l² will be moved

by the needle l to fixed contact l³, and a circuit will be completed through all of the contacts, the current then passing from battery J' through wire 24 to contact l', through wire 26, contacts l³ and l², needle l, wire 22, bell H², back to battery J' through wire 23, the switch in wire 25 being open, as already explained.

In Figs. 3, 4, and 5 I show another form of circuit-closing device in the form of a galvanometer having two armatures and two needles operating as separate movable contacts. The needle m, with its armature m', is pivotally mounted in the usual manner within the coil M, the latter being wound upon a spool or frame M'. The needle n is attached to an armature n', pivotally mounted in suitable bearings above the armature m, and has a central opening n², through which the needle m projects, the two armatures, with their needles, being thus permitted to vibrate independently of each other. Mounted upon the frame M' and between the two needles m and n and parallel with their line of motion is a plate or standard o, having slots o' and o², in which the electrical contacts p, p', and p² are adjustably mounted. Contacts p and p' are mounted in slot o' at each side of the needle m and in the path of its travel. Contact p² is mounted in slot o² in line with the path of needle n, the latter being bent through said slot to bring its tip to the front of the plate o, as clearly shown. Both needles of this instrument are controlled by the coil M, through which the main-line current passes, as in the other instruments before described. The movable and fixed contacts are coupled to the alarm-circuit as follows: Connected with one pole of a battery J² is a wire 27, leading to bell H³, and from bell H³ a wire 28 connects with both of the movable contacts or needles m and n. This wire 28 is connected to a binding-post q, Fig. 4, from which a wire 29 connects to a screw 30, secured in the frame m², supporting the armature m'. From this point the electrical connection to the needle m is through frame m² to the armature-shaft m³, through wire 31 to needle m. The connection from screw 30 to needle n is through wire 32 to bearing-plate n² to armature-shaft n³, through wire 33 to needle n. The supporting-shafts of both armatures are mounted in insulating-blocks, as clearly shown. From the other pole of battery J² a wire 34 leads to fixed contact p, which is connected by wire 35 to fixed contact p². A second wire 36 leads from the same battery-pole to fixed contact p'. The wires 34, 36, and 35 are each provided with switches h h' h² for opening the circuit, as before described. The operation of needle m in connection with fixed contacts p and p' is the same as the needle of galvanometer G of Fig. 1, and the operation of needle n in connection with its fixed contact p² is the same as that of galvanometer K of

Fig. 1, and each needle, with its fixed contacts, may be coupled in separate circuits instead of the single circuit shown. The movable contacts m and n are shown in the position they occupy when the resistance F is in the main-line circuit, and they both move together when said resistance is cut out, and needle m will then complete the alarm-circuit by coming in contact with fixed contact 5 p' ; but needle n will be held by resistance K' away from its fixed contact p^2 and until said resistance is cut out by a short circuit outside of the protected building. When resistance F is out of the main line, needle m will 10 rest against contact p' and needle n will be separated by a short space from contact p^2 . The alarm-circuit being closed by the needle m it is opened at switch h' . Should the main line then become short-circuited, resistance 15 K' will be cut out and needle n deflected against contact p^2 and give the alarm. The armature n' of needle n is weighted, as at n^4 , to lessen its range of movement, as explained in connection with galvanometer K of Fig. 1.

20 Having thus described my invention, what I claim as new, and desire to secure by Letters Patent, is—

25 1. In a burglar-alarm system the combination of a normally-closed main line connecting an alarm-station with a structure to be protected, circuit-closing devices operated by an increase in the current of the main line for closing separate or branch alarm-circuits, and a resistance for controlling one of said 30 circuit-closers independently of the operation of the other, substantially as described.

35 2. In a burglar-alarm system the combination with a normally-closed main line connecting an alarm-station with a structure to be protected, of a resistance normally within said main line, a protecting-circuit within the protected structure independent of the main circuit, and means whereby a break or short circuit in the protecting-circuit will operate to cut said resistance out of the main 40 line, substantially as described.

45 3. In a burglar-alarm system the combination of a normally-closed main line connecting an alarm-station with a structure to be protected, a resistance adapted to be cut into or out of circuit therewith, a protecting-circuit consisting of separate local circuits each independent of each other and of the main line, an annunciator to which each of said local 50 circuits is connected, and means whereby a short circuit or break in any of said local circuits will operate through said annunciator to cut out said resistance, substantially as described.

55 4. In a burglar-alarm system, the combination of a normally-closed main line connecting an alarm-station with a structure to be protected, a resistance normally within said main line, a protecting-circuit consisting of separate local circuits each independent of each other and of the main line, electromagnets

in each of said local circuits, armatures controlled by said magnets, and contacts connected to the main-line circuit adapted to be engaged by said armatures when released by 70 said magnets for grounding the main line and cutting out said resistance, substantially as described.

5. In a burglar-alarm system, the combination of a normally-closed main line connecting 75 an alarm-station with a structure to be protected, circuit-closing contacts controlled by variations in the condition of the main-line current for closing separate or branch circuits, a resistance adapted to be cut into or out of said main line, a protecting-circuit provided with devices for cutting said resistance out of the main-line circuit, and a second resistance in the main line for controlling the movement of one set of contacts independently of the other, substantially as described.

6. In a burglar-alarm system the combination of a normally-closed main line connecting an alarm-station with a structure to be protected, a resistance adapted to be cut into or out of circuit therewith, circuit-closing contacts controlled by variations in the main-line current for closing an alarm-circuit when said resistance is cut out, a second set of contacts 90 also controlled by variations in the main-line current for closing a separate or branch alarm-circuit, and a second resistance in the main line for preventing the closing of said second set of contacts when said first-mentioned resistance is cut out, substantially as described.

7. In a burglar-alarm system the combination of a normally-closed main line connecting an alarm-station with a structure to be protected, a resistance adapted to be cut into or out of circuit therewith, a protecting-circuit in the guarded structure provided with means for cutting out said resistance, a second resistance in the main line, separate sets of contacts controlled by variations in the main-line current for closing separate or branch alarm-circuits so adjusted with reference to each other and to said second resistance, that the circuit controlled by one set of contacts will remain open after the circuit controlled 105 by the other set of contacts has been closed by the cutting out of the first-mentioned resistance, substantially as described.

8. In a circuit-closing instrument adapted to be controlled by variations in the condition 110 of an electric current, the combination of a coil, a pair of armatures pivotally mounted within said coil independently of each other, contacts carried by each armature, and adjustable contacts mounted in the path of the 115 before-mentioned contacts, substantially as described.

9. In a circuit-closing instrument adapted to be controlled by variations in the condition 120 of an electric current, the combination of a coil, a movable contact consisting of an armature and needle pivotally mounted within

said coil, an adjustable contact in the path of said movable contact, a second movable contact also consisting of an armature and needle pivotally mounted within said coil and an
5 adjustable contact in the path thereof, one of said movable contacts being weighted at one side opposite to the adjustable contact with which it engages, substantially as described.

In testimony whereof I have hereunto set my hand in presence of two subscribing wit- ^{to} nesses.
